UNITED STATES PATENT OFFICE.

PATRICK J. COLLINS AND CHRISTOPHER G. BOLAND, OF SCRANTON,
PENNSYLVANIA.

ELECTRIC BODY APPLIANCE.

SPECIFICATION forming part of Letters Patent No. 710,429, dated October 7, 1902.

Application filed January 22, 1902. Serial No. 90,769. (No model.)

To all whom it may concern:

Be it known that we, PATRICK J. COLLINS and CHRISTOPHER G. BOLAND, citizens of the United States, residing at Scranton, in the 5 county of Lackawanna, State of Pennsylvania, have invented certain new and useful Improvements in Electric Body Appliances, of which the following is a specification.

This invention relates to appliances for the 10 purpose of applying electric current to different parts of the body for the purpose of stimulating the circulation of the blood and maintaining the parts at their normal temperature.

15 The invention comprises a belt containing a connected series of battery-cells, a motor-transformer attached to the belt and operated from the batteries, a garment having suitable conducting portions and circuits leading 20 thereto from the transformer through a miniature distributing-board, and devices for regulating the current.

In the accompanying drawings, Figure 1 is 25 a view showing the garment with the belt in position and the circuits. Fig. 2 is an enlarged view of a portion of the belt, including the transformer, which is shown in section, and the circuits. Fig. 3 is a rear view of the upper portion of the garment.

30 Referring to the drawings, *a* indicates a belt which is to be worn about the body and containing a connected series of batteries *b*. Connected between the ends of the belt is a box *c*, containing a motor-generator *d*, a relay *e*, and an inductive resistance *f*. A circuit *1* leads from a terminal cell *2* of the battery by way of the relay *e* to the motor, thence to a variable-resistance device *3*, and to the other terminal cell *4* of the battery.

40 The motor, as shown, is shunt-wound, but may be otherwise wound. The resistance-switch *3* is arranged upon a suitable board *5*, adapted to be inserted in the vest-pocket or elsewhere on the clothing. A thermostat *g* 45 is connected by a circuit *6* to a single cell of the battery and extends around the magnet-coil of the relay *e*. This thermostat may be placed upon any part of the body, such as the feet, and when the temperature falls the thermostat closes the relay-circuit and draws the 50 armature *7* into contact with the clip *8*, there-

by closing the primary circuit of the motor-transformer and starting it into action. A circuit *9*, leading to a switch *10* upon the board *5*, is connected to the motor-circuit *1* on opposite sides of the relay, so that the motor may be started into operation by moving the switch *10*, so as to short-circuit the relay. The apparatus may thus be used with or without the thermostat. Upon the rear end of the motor-shaft is arranged an insulated ring *11*, which is connected by a wire *12* to one segment of the commutator *13*, and a wire *12a* connects an opposite segment through the shaft to a metal disk *14* upon the opposite end of the shaft. A wire *15* leads from the insulated ring *11* to a binding-post *16* upon a distributing-board *17*. From a brush resting upon the disk or ring *14* a wire *18* leads to a coil *19* upon an iron core *20*, and the opposite end of this coil is connected by a wire *21* to a conducting-section *22*, which is arranged in the back of the garment and extends along the spinal column. A coil *23* is wound upon the core *20*, and a circuit *24* extends from this coil to the switchboard *5*, said circuit including an adjustable resistance *25* upon the board.

It will be seen that when the motor-circuit is closed either by the thermostat *g* or the switch *10* an alternating current will be generated in the transformer, which will be conducted through the sliding contacts upon the rings to the binding-post *16* and conducting-surface *22*. The frequency of this current may be regulated by regulating the speed of the motor through the variable resistance *3*, and its voltage and volume may be regulated independently of the frequency by varying the resistance *25*, which is in the secondary circuit of the inductive resistance device *f*. The relay is placed in circuit in order that the transformer may be started by the passage of a small current through the thermostat. If the thermostat were inserted directly in the motor-circuit, its points of contact would soon be corroded and the device rendered inoperative by the comparatively large quantity of current which it would necessarily have to carry.

As shown in Fig. 1, the garment *h* is provided with a number of disconnected conducting-surf 100 faces *h' h² h³*, &c., and *i' i² i³*, &c.

These are preferably formed by weaving into the garment fine wire or tinsel cord, which comes in contact with the body, and each of these conducting-surfaces, with the exception of the surface 22, is connected by a fine insulated wire in a separate terminal pin upon the distributing-board 17. The pins $j' j^2 j^3$, &c., are connected, respectively, to the pads $h' h^2 h^3$, &c., upon the right side of the body, while the pins $k' k^2 k^3$, &c., are connected to the corresponding pads $i' i^2 i^3$ upon the left side of the body. A small hook 26, which is connected by a flexible wire 27 to the binding-post 16, is adapted to hook over any one of the pins, and thus connect the wire 15, leading from the transformer, to any given pad or conducting-surface in the garment. Thus by connecting the hook to the pin j' a current may be sent from the right shoulder through the body to the conducting-surface 22 on the spinal column, or by connecting the hook to the pin k^6 a current may be sent to the left ankle and thence through the body to the pad 22, and so on. In this way the current may be applied to stimulate any portion of the body, or when the patient is in normal condition the switch may be opened and the current shut off. One or more thermostats may be used, if desired, or the thermostat may be dispensed with. By operating the resistance device 3, which controls the speed of the motor, the frequency of the current may be changed to suit the patient, and by operating the resistance 25 the voltage and current may be varied without varying the frequency. The conducting-surfaces may be made separately and attached to the garment; but they are preferably woven into and form a part of the garment, and they may be differently located and connected. The distributing-pins and the regulating devices may be all arranged upon a single board, so as to be carried in one vest-pocket, instead of being on separate boards, as shown in the drawings, the arrangement upon separate boards in the drawings being simply for the purpose of convenience and clearness in illustration. In the drawings also the circuits leading from the apparatus and the conducting-surfaces to the

boards are shown diagrammatically; but it will be understood that in practice the various circuits leading from the garment and the transformer will be combined into a single cable, which may be brought out through the front of the clothing to the board. 55

Having described our invention, what we claim, and desire to secure by Letters Patent, is—

1. The combination with a belt and a suitable source of electricity carried thereby of a garment having a conducting-surface in the back thereof and conducting-surfaces in various other parts of the garment, a return-circuit leading from said back conducting-surface to one pole of the source of electricity and circuits, and a switching device arranged to connect the opposite pole with the other conducting-surfaces. 60

2. In an electric body appliance a combination with a belt having a battery thereon of a motor-generator, circuits connecting said motor-generator with the battery, a garment having conducting-surfaces thereon and circuits leading from the motor-generator to said surfaces. 70

3. The combination with a belt having batteries thereon of a motor-generator carried by the belt, a garment having conducting-surfaces thereon, circuits leading from the generator to said surfaces, a relay arranged to close the motor-circuit and a thermostat arranged to operate the relay. 75

4. The combination with a belt having batteries thereon, and a motor-generator, carried by the belt and arranged to produce an alternating current, of a garment having conducting-surfaces, circuits leading from the generator to said conducting-surfaces, means for varying the speed of the motor, and means for regulating the voltage of the alternating current. 85

In testimony whereof we affix our signatures in presence of two witnesses.

PATRICK J. COLLINS.
CHRISTOPHER G. BOLAND.
